(57) **CLAIM**

The ornamental design for a deodorant dispenser, as shown and described.

DESCRIPTION

FIG. 1 is a perspective view of a deodorant dispenser. FIG. 2 is a back view of the deodorant dispenser of FIG. 1. FIG. 3 is a front view of the deodorant dispenser of FIG. 1. FIG. 4 is a left side view of the deodorant dispenser of FIG. 1. FIG. 5 is a right side view of the deodorant dispenser of FIG. 1.

FIG. 6 is a bottom view of the deodorant dispenser of FIG. 1. FIG. 7 is a top view of the deodorant dispenser of FIG. 1; and, FIG. 8 is an exploded perspective view of the deodorant dispenser of FIG. 1.

The broken line showing of a deodorant dispenser represents unclaimed subject matter and forms no part of the claimed design.
